UNITED STATES PATENT OFFICE.

HARRY JOSEPH BUR, OF PHILADELPHIA, PENNSYLVANIA, ASSIGNOR TO ELLSWORTH L. WARD, HARRY JOSEPH BUR, AND RUDOLPH H. BECK, TRADING AS CLIMAX HOIST COMPANY, OF PHILADELPHIA, PENNSYLVANIA.

CHAIN HOIST.

No. 892,973.

Specification of Letters Patent.

Patented July 7, 1908.

Application filed February 24, 1908. Serial No. 417,303.

To all whom it may concern:

Be it known that I, HARRY JOSEPH BUR, a citizen of the United States, residing at Philadelphia, in the county of Philadelphia and State of Pennsylvania, have invented certain new and useful Improvements in Chain Hoists, of which the following is a specification.

This invention relates to hoisting apparatus, and has special reference to that class of hoists which are operated usually by hand power and are employed for lifting heavy articles in warehouses, storage rooms, or the like, and includes novel devices hereinafter specified and claimed.

For a full understanding of the invention, including its construction and characteristic advantages, reference is to be had to the following detail description and to the accompanying drawings, in which,

Figure 1 is a side elevation of the apparatus; Fig. 2 is a front elevation of the same; Fig. 3 is a vertical sectional view; Fig. 4 is a partial section taken on the line 4—4 of Fig. 3, and Fig. 5 is a similar view taken on the line 5—5 of Fig. 3.

Throughout this description and on the several views of the drawings, similar parts are referred to by like reference characters.

This invention, in its preferred embodiment comprises a supporting trolley 10, supported upon and movable along an I-beam 11. Suspended from said trolley 10 by any suitable means such as a hook 12 is the main portion of the hoist 13. Said hoist comprises a frame 14 of any suitable construction and material. A load wheel 15 is situated substantially in the center of said frame and is secured rigidly, and by a key, to a member 16 comprising a hollow arbor and an end gear 17 integral therewith. The said member 16 is journaled for rotation in the frame 14 preferably by antifriction bearings. Meshing with the gear 17 is a pinion 18 secured to or integral with an internal gear 19 and journaled for rotation on a stud 20 secured to the main frame of the hoist. The gear 19 intermeshes with a pinion 21 secured to a central shaft 22 operating within the member 16 aforesaid. The end of the shaft 22 opposite to the pinion 21 has keyed to it a clutch member 23, having at one end an outwardly extending flange 24, the other end of the

said clutch member being exteriorly screw threaded at 25. Mounted upon the threaded end of said clutch member is a wheel 26 designed to be operated by any suitable means as by a hand chain 27. The wheel 26 is internally screw threaded for direct coöperation with the threaded portion of the member 23 when rotated. Between the inner face of the hand wheel 26 and the outer face of the flange 24 are interposed a plurality of friction disks 28, and coöoperating therewith and journaled loosely on the hub of the member 23 is a ratchet wheel 29 adapted to be held from backward rotation by a pawl 30.

Thus far described the operation of the hoist is as follows: Power being applied to rotate the handle wheel, say toward the right or clockwise, the first effect will be for said wheel to tighten up the disks 28 causing the ratchet wheel 29 and the member 23 to become sufficiently secured together for the wheel to cause rotation of the shaft 22, and a continued rotation of the shaft 22, through the pinions and gears above described, will cause rotation of the load wheel 15, thereby hoisting the load. Upon release of the power from the hand wheel the load will be automatically held suspended at the point to which it has been elevated. This result is due to the immediate automatic effect of the pawl 30 in coöperation with the ratchet wheel 29 which is securely clutched to the member 23. In order to lower the load a slight reverse movement of the hand wheel is sufficient to allow the clutch members to slip with respect to the ratchet wheel 29, whereby the load will be run down due to its own weight. The speed, however, at which the load will descend will be determined by the amount of movement of the hand wheel in the reverse direction, it being impossible for the load to descend more rapidly than will be permitted by said hand wheel.

The trolley 10 to which reference has heretofore been made comprises a substantially U-shaped yoke 31 to which the hook 12 is or may be directly connected. Said yoke is connected on each side of the I-beam 11 to the central portion of a side plate 32, such connection being a pivotal one. Each of the side plates 32 has journaled thereto a plurality of trolley wheels 33, one at each end. The engaging face of each of the wheels 33 is

preferably spherical, in order to reduce the amount of frictional contact between it and the supporting flange of the I-beam. From this construction of the trolley it will be apparent that the load carried thereby will always be equally distributed among all four of the supporting wheels, a matter of a great deal of importance from a practical standpoint.

10 Having thus described the invention, what is claimed as new, is:

1. The herein-described hoisting apparatus comprising a frame, a hollow member journaled in said frame and having an internal gear integral therewith, a pinion in mesh with said internal gear, a second internal gear secured to said pinion, a second pinion in mesh with the second internal gear, a shaft to which the latter pinion is secured and journaled for rotation within said hollow member, a clutch secured to said shaft, the clutch having a screw thread, a hand wheel having an interior screw thread coöoperating with said clutch member to cause rotation of

said shaft, and a load wheel secured to said hollow member.

2. A hoist comprising, in combination, a frame, a hollow member antifrictionally journaled therein, an internal gear integral with one end of said hollow member, a shaft journaled within said hollow member, a pinion secured to one end of said shaft, intermeshing gears between said internal gear and said pinion, a clutch member keyed to the opposite end of said shaft, said clutch member being exteriorly screw threaded and provided with an outwardly projecting flange, a hand wheel screw threaded upon said clutch member, friction disks between the hand wheel and said flange, a ratchet wheel loosely mounted between said friction disk, and a pawl coöoperating with said ratchet wheel.

In testimony whereof I affix my signature in presence of two witnesses.

HARRY JOSEPH BUR.
